FLASHLIGHT FOR MINERS' CAPS OR THE LIKE

Warren B. Beers, 624 40th St. N.E., Cedar Rapids, Iowa

Filed Apr. 25, 1960, Ser. No. 60,299

Term of patent 14 years

(Cl. D48—24)

I claim:

The ornamental design for a flashlight for miners' caps or the like, as shown.
